(57) **CLAIM**

The ornamental design for a surgical drill, as shown and described.

DESCRIPTION

FIG. 1 is a perspective view of a surgical drill, as viewed from the top and front.

FIG. 2 is a front side profile view of the surgical drill.

FIG. 3 is a back side view of the surgical drill.

FIG. 4 is a right side profile view of the surgical drill.

FIG. 5 is a left side profile view of the surgical drill.

FIG. 6 is a top plan profile view of surgical drill; and, FIG. 7 is a bottom plan profile view of the surgical drill. The details shown in dash-dash broken lines illustrate features of the surgical drill that form no part of the claimed design. The dot-dash circle depicts a boundary to the claim and forms no part of the claimed design.
